UNITED STATES PATENT OFFICE.

JOHN HEINONEN, OF BRUSH PRAIRIE, WASHINGTON.

METAL RAILWAY-TIE.

977,798.

Specification of Letters Patent.

Patented Dec. 6, 1910.

Application filed August 24, 1910. Serial No. 578,645.

To all whom it may concern:

Be it known that I, JOHN HEINONEN, a citizen of the United States, residing at Brush Prairie, in the county of Clarke, 5 State of Washington, have invented certain new and useful Improvements in Metal Railway-Ties; and I do hereby declare the following to be a full, clear, and exact description of the invention, such as will enable 10 others skilled in the art to which it appertains to make and use the same.

This invention relates to improvements in railway ties and has for one of its objects to provide a simple tie constructed wholly of 15 a piece of metal bent into the required shape and reinforced longitudinally.

Another object of the invention is to provide a metal railway tie formed from a single plate of metal bent into the required 20 shape and reinforced longitudinally and provided with rail recesses, and so arranged that the binding bolts whereby the rails are supported in position are also utilized to fasten the reinforcing portions of the device 25 to the body of a tie.

With these and other objects in view, the invention consists in certain novel features of construction as hereinafter shown and described; and, then specifically pointed out 30 in the claims.

Figure 1 is a perspective view of the blank from which the improved tie is produced. Fig. 2 is a side elevation of the improved tie with the rails arranged thereon and in 35 section. Fig. 3 is a plan view of the improved tie with one of the rails thereon. Fig. 4 is an end elevation of the improved tie. Fig. 5 is a section on the line 5—5 of Fig. 3.

40 The improved tie is constructed wholly from a single plate of metal represented as a whole at 10 in Fig. 1, and is bent into the required shape, and the form of the plate prior to being bent is represented in Fig. 1, 45 and is formed with two depressions 11—12 extending partly through the metal of the plate and spaced apart a distance equal to the space between the rails, the depressions 11—12 being designed to form seats to receive the rails when the tie is bent into shape as hereinafter explained. Formed in the 50 edges of the plate 10 opposite to the depressions 11—12 are recesses 13, the object to be hereinafter described: The plate 10 is bent 55 along the dotted lines 14 into the shape shown in Figs. 2 and 3, that is to say, bent

into oblong form transversely, with vertical webs 15—16 bearing face to face mid-way between the side walls 17—18 of the body of the tie and with flanges 19—20 bearing 60 beneath the top portion 21. By this means the tie is formed into two equal compartments extending longitudinally of the tie with the webs 15—16 arranged centrally thereof and supporting the upper member 65 21. The depressions 11—12 are of sufficient length so that when the tie is bent into the shape shown in Figs. 4 and 5 the depressions will extend over the entire width of the top member 21, and form seats for the rails 70 represented at 22. When the tie is bent into the form shown in Figs. 4 and 5 the recesses 13 come wholly within the flanges 19—20 and bear around the under sides of the depressions 11—12, so that the body portions 75 of the flanges bear against the under face of the upper web 21 of the tie. The flanges 19—20 are secured by suitable rivets 23 to the upper web 21, and the upper web and the flanges are provided with registering apertures or slots 24 to receive the bolts 25 by 80 which the rails are secured in place, the bolts having laterally extending heads 27 to bear upon the tie flanges of the rails. The bolts 25 are provided with binding nuts 28 on 85 their lower ends and engage against the lower faces of the flanges, so that the binding bolts 25 perform the two-fold function of means for clamping the upper web 21 to the flanges, and also means for holding the 90 rails in place. The depressions 11—12 are formed angular at one side, and are wider than the tie flanges of the rails, to provide means for the insertion of wedging keys 29 95 which form means for tying the rails firmly in position and preventing lateral movement.

The heads 27 of the bolts extend over the keys 29, and likewise extend over a portion of the tie flanges of the rails, so that the bolt 100 heads prevent any upward movement or vertical displacement of the keys.

The plate 10 may be of any required thickness or gage of metal, and will be of the ordinary length of a railway tie, usually about 105 eight feet, and of sufficient width so that when bent into the required shape the tubular member will be of the usual size of a metal tie, or about eight inches wide and four inches thick, but these dimensions may 110 be varied if required. The wedge keys 29 will be long enough at the smaller end to

project beyond the tie so that the projecting end can be bent down over the tie as indicated in Fig. 3, to prevent the displacement of the key.

5. What is claimed is:—

1. A railway tie constructed of a plate of metal bent to form an oblong tube with a continuous top and a divided bottom and central vertical webs bearing back to back and extending between the top and bottom members, the upper edges of the vertical webs being extended laterally and bearing beneath the continuous top, and fastening devices extending through the flanges and 15 the continuous top.

2. A railway tie constructed of a plate of metal bent to form an oblong tube with a continuous top having rail receiving depressions and a divided bottom and with central 20 vertical webs bearing back to back and extending between the top and bottom members, the upper edges of the vertical webs being extended laterally and bearing beneath the continuous top, and fastening devices 25 tending through the flanges and the continu-

ous top and provided with lateral heads for bearing upon the rails supported in said depressions.

3. A railway tie constructed of a plate of metal bent to form an oblong tube with a continuous top having rail receiving depressions oblique at one side to the transverse axis of the tie, and a divided bottom and central vertical webs bearing back to back and extending between the top and bottom 35 members, the upper edges of the vertical webs being extended laterally and bearing beneath the continuous top, fastening devices extending through the flanges and the continuous top and provided with lateral heads 40 for bearing upon the rails supported in said depressions, and wedge keys within said depressions and bearing against the rail and the oblique sides of the depressions.

In testimony whereof, I affix my signature, 45 in presence of two witnesses.

JOHN HEINONEN.
